PHOTOGRAPHIC FLASH LAMP OR SIMILAR ARTICLE

Sidney H. Bradd, Jr., New York, N.Y., Edison R. Brandt, Marblehead, Mass., and Robert H. Ensign, Bronxville, N.Y., assignors to Polaroid Corporation, Cambridge, Mass., a corporation of Delaware

Application June 25, 1958, Serial No. 51,540

Term of patent 14 years

(Cl. D61—1)

Figure 1 is a front perspective view of a photographic flash lamp or similar article, showing our new design; and Figure 2 is a rear perspective view thereof, in both figures, the broken line fragmentary showing of a camera with which the lamp may be used being for illustrative purposes only.

We claim:

The ornamental design for a photographic flash lamp or similar article, substantially as shown and described.
